UNITED STATES PATENT OFFICE

WILLIAM W. TOBEY AND FRED FREEMAN, OF IOLA, KANSAS.

ICE-MACHINE.

No. 873,189.

Specification of Letters Patent.

Patented Dec. 10, 1907.

Application filed September 25, 1905. Serial No. 280,068.

To all whom it may concern:

Be it known that we, WILLIAM W. TOBEY and FRED FREEMAN, citizens of the United States, residing at Iola, in the county of Allen and State of Kansas, have invented a new and useful Ice-Machine, of which the following is a specification.

This invention relates to machines employed in manufacturing ice, and has for its object to improve the construction, and increase the efficiency and utility of devices of this character.

With these and other objects in view which will appear as the nature of the invention is better understood, the invention consists in certain novel features of construction as hereafter fully described and claimed.

In the accompanying drawings forming a part of this specification and in which corresponding parts are denoted by like designating characters, is illustrated the preferred form of the embodiment of the invention capable of carrying the same into practical operation, it being understood that various changes in the form, proportions, and minor details of construction may be resorted to without departing from the principle or sacrificing any of the advantages of this invention within the scope of the appended claims.

30 In the drawings:—Figure 1, is a plan view of the improved apparatus with the top member or frame removed. Fig. 2 is an enlarged sectional detail illustrating the manner in which the freezing mixture is applied to the cans or receptacles for the water to be frozen. Fig. 3 is a longitudinal sectional elevation, and Fig. 4, is a transverse section on the line 4—4 of Fig. 3. Fig. 5 is a detail view illustrating a modification in a portion 40 of the structure.

The improved apparatus may be of any required size and capacity or of any required material, but for the purpose of illustration is shown arranged for twelve of the freezing 45 cans or receptacles of the usual form.

The improved apparatus consists of an outer casing 10, preferably of wood with a sheet metal lined bottom 11, inclining from each side toward the center and merging into 50 a longitudinal trough or channel 12 into which matter falling upon the bottom 11 will be drained.

Disposed transversely of the bottom 11 of the casing are bars 13 spaced apart, and preferably two for each transverse row of the freezing receptacles or cans, and with their

lower faces conforming to and bearing upon the doubly inclined bottom, and each with a central upwardly extending recess 14 above the drainage channel 12. Disposed longitudinally of the cross bars 13 are spaced rails 15, one for each longitudinal row of the freezing cans and preferably recessed in the bars.

The inner faces of the vertical walls of the casing 10 are provided with numerous spaced vertical guide channels 16, in which the ends of spaced longitudinal partitions 17 and transverse partitions 18 are supported, the partitions being "halved" into each other, or otherwise united or coupled where they transect, and forming the interior of the casing into a plurality of rectangular chambers or compartments of uniform size.

The lower ends of the channels 16 terminate above the bottom 11, so that the partitions are supported above the bars 13 and rails 15, and a space is left between partitions and the "grating" formed by the bars and rails, while the upper edges of the partitions terminate below the upper line of the casing, and thus provide a space above the partitions and within the casing.

The trough portion 12 of the apparatus extends through the end wall of the casing and terminates in a flange 35 supporting a closure 36, which is detachably secured to the flange by bolts 37.

Disposed in the trough 12 is a tube formed in sections 38 with flanged ends 39, whereby the sections are detachably coupled as by bolts 40, each section having an annular shoulder 41 next its flange to support wire netting shields 42 surrounding each tubular section and spaced from the same, and with a wire netting diaphragm 43 at the inner end of the last tubular section. The tubular sections 38 are each provided with numerous apertures 44 providing means for the entrance of the liquid after it passes through the wire netting guards. The tubular member 38 which comes next to the closure 36, is connected to the closure member, and the latter is provided with a central aperture corresponding to the interior area of the members 38, and the pump for removing the freezing liquid, after it has performed its work, is connected as at 45 to the closure 36.

The netting guards 42—43 prevent the entrance of foreign matter to the tubular sections 38, and as a still further protection, a wire netting guard 46 is disposed over the channel 12 and its tubular drainage mem-

ber, and attached to the cross bars 13 within the recess 14, so as to be removable with the grating.

The freezing receptacles or cans 19 are of the usual form, or rectangular in cross section, and with all the side walls tapering inwardly toward the lower end. The receptacles rest upon the grating formed by the bars 13 and rails 15, two of the bars and one 10 of the rails being beneath each receptacle, and with the upper rims of the receptacles strengthened by a strap iron band 20, and each receptacle also provided with apertures 21 to receive the instrument or grapple by which they are deposited into and removed from their places within the casing.

The top of the casing is in the form of a frame 22, supported by transverse and longitudinal rails 23-24, the rails corresponding to and disposed above the partitions 17-18 and spaced above the same, so that a space is provided between the rails and the upper edges of the partitions. The rails 23-24 form rests for numerous detachable 25 covers 25, one for each compartment, so that one or more of the receptacles may be removed or inserted without interfering with or disturbing the others.

Extending into the casing 10 at one end is 30 a supply pipe 26 for the freezing mixture, the supply pipe preferably disposed partly within the adjacent end wall of the casing as shown in Figs. 1 and 3, so that it will not interfere with the introduction or removal of 35 the receptacles. Extending from the supply pipe 26 are longitudinal branch pipes 27, two of the branches contiguous to the side walls of the casing and one branch above each of the longitudinal partitions 17. Leading 40 from one of the outside longitudinal branches and from all of the intermediate longitudinal branches, are shorter transverse branches 28, the latter extending nearly to the next longitudinal branch in advance, and with the 45 outer end of each shorter branch plugged as indicated at 29, the shorter branch pipes being disposed above the transverse partitions 18.

The main supply pipe 26 and branch pipes 50 27-28 are supplied with spaced "pin hole" apertures respectively at 32-33-34, disposed in the lower portions of the several pipes, so that the liquid forced therefrom will strike the sides of the receptacles at 55 downwardly projecting angles, as illustrated in Fig. 2 wherein the radiating lines represent the jets of the freezing liquid.

The freezing compound or "brine" is stored in a suitable tank, not shown, and 60 supplied under suitable pressure to the main pipe 26 and flows thence to the various branch pipes 27-28 and escapes in fine sprays upon the upper portions of the freezing receptacles and equally upon all sides of 65 the same. The upper edges of the partitions

17-18 are chambered upon each side at the upper edges as at 30-31, to reduce the area adjacent to the pipes 27-28 respectively, to avoid obstructing the discharge from the apertures in the pipes. It will be noted that 70 the jets of the freezing mixture engage the receptacles 19 first near the top and flow downward over the outer surface, and thus effect a more rapid refrigeration than in devices where the receptacles are immersed in 75 the freezing medium, as the very rapid circulation of the liquid insures a very rapid absorption of the heat and the consequent rapid congealing of the water in the receptacles. The free escape for the freezing 80 mixture obviates any danger of the deterioration of the water in the receptacles in event of any leakage in the same, as the brine will not enter such apertures, as will be 85 obvious.

The arrangement of the spray pipes enables the desired results to be accomplished with a comparatively small quantity of brine, and in a shorter space of time than in devices wherein the receptacles are immersed in 90 the freezing compound.

The apparatus can be readily drained and cleaned without removing the receptacles, piping, racks, or partitions, or other parts, by merely detaching the pump coupling and 95 closure 36, and removing the tubular sections 38, to provide means for the insertion of the cleaning implements, or in large devices of a man or boy to perform the work.

The device is simple in construction, can 100 be inexpensively manufactured and economically operated.

The minute apertures for the escape of the liquid from the pipes 26-27 and 28 may be in the form of slots as at 47 in Fig. 5, if preferred.

Having thus described the invention what is claimed is:

1. In an apparatus for manufacturing ice, a plurality of receptacles for the water to be frozen arranged in rows spaced apart and with the receptacles in each row likewise spaced apart, pipes arranged exteriorly of the outer rows and within the spaces between the rows and provided with branch pipes extending between the receptacles in the rows, said pipes having spaced orifices discharging toward the receptacles and adapted to supply the freezing compound simultaneously to all the sides of all the receptacles.

2. In an apparatus for manufacturing ice, an inclosing casing, a plurality of partitions dividing the interior of the casing into a series of compartments, a plurality of receptacles arranged one in each of said compartments and supported above the bottom of said casing, and a series of pipes arranged above said partitions and provided with spaced lateral apertures opening toward said receptacles.

3. In an apparatus for manufacturing ice,

- an inclosing casing having a discharge for the freezing medium, a plurality of receptacles for the water to be frozen and spaced apart within said casing and supported above 5 the bottom of the same, and a series of pipes for the freezing medium extending between said receptacles and provided with spaced lateral apertures opening toward said receptacles.
- 10 4. In an apparatus for manufacturing ice, an inclosing casing having a discharge for the freezing medium, a plurality of receptacles for the water to be frozen and spaced apart within said casing and supported 15 above the bottom of the same, and a series of pipes for the freezing medium extending between said receptacles near their upper parts and provided with spaced lateral apertures arranged to cause sprays of the freezing 20 medium to be discharged against the receptacles at downwardly extending angles.
5. In an apparatus for manufacturing ice, an inclosing casing having an inclined bottom terminating in a depressed discharge 25 trough for receiving the freezing medium after its action upon the freezing receptacles, a detachable grating, bearing upon said casing bottom, a plurality of receptacles for the water to be frozen spaced apart and supported upon said grating, and pipes for the 30 freezing medium extending between said receptacles and provided with spaced lateral apertures opening toward said receptacles.
6. In an apparatus for manufacturing ice, 35 an inclosing casing having an inclined bottom terminating in a depressed discharge
- trough for receiving the freezing medium after its action upon the freezing receptacles a detachable grating bearing upon said casing bottom, a plurality of partitions dividing 40 said casing into a series of compartments, a plurality of receptacles for the water to be frozen arranged one in each of said compartments, and bearing upon said grating, and a series of pipes arranged above said partitions 45 and provided with spaced lateral apertures opening toward said receptacles.
7. In an apparatus for manufacturing ice, an inclosing casing having an inclined bottom terminating in a depressed trough for 50 receiving the freezing medium after its action upon the freezing receptacles, a receiving tube within said trough and provided with a plurality of spaced lateral apertures and spaced lateral flanges, a sheathing of 55 screen material inclosing said tube and supported by said flanges, a detachable grating bearing upon said casing bottom and above said trough, a plurality of receptacles for the water to be frozen spaced apart and supported upon said grating, and pipes for the 60 freezing medium extending between said receptacles and provided with spaced lateral apertures opening toward said receptacles.
- In testimony that we claim the foregoing 65 as our own, we have hereto affixed our signatures in the presence of two witnesses.

WILLIAM W. TOBEY.
FRED FREEMAN.
